COMBINATION AIR FILTERING AND COLLECTING UNIT FOR TEXTILE WASTE PRODUCTS

R. Hovan Hocutt and Thomas E. Mullinax, Charlotte, N.C., assignors to Pneumafil Corporation, Charlotte, N.C., a corporation of Delaware

Filed Feb. 14, 1964, Ser. No. 78,632

Term of patent 14 years

(Cl. D9—2)

FIG. 1.

FIG. 2.

FIG. 3.

FIG. 4.

FIG. 1 is a front perspective view of a combination air filtering and collecting unit for textile waste products embodying our new design;

FIG. 2 is a rear perspective view thereof;

FIG. 3 is a front perspective view of the design covered by FIGS. 1 and 2;

FIG. 4 is a rear perspective view thereof.

We claim:

The ornamental design for a combination air filtering and collecting unit for textile waste products, as shown.
